US00D656815S

(12) **United States Design Patent**
Fisher et al.

(10) **Patent No.:** **US D656,815 S**
(45) **Date of Patent:** **** Apr. 3, 2012**

(54) **CONTAINER**

(75) Inventors: **Scott L. Fisher**, Evansville, IN (US);
Monica Beth Ciaramitaro, Broomfield,
CO (US); **Tom Walker**, Evansville, IN
(US); **Ray Fallen**, Evansville, IN (US)

(73) Assignee: **Berry Plastics Corporation**, Evansville,
IN (US)

(**) Term: **14 Years**

(21) Appl. No.: **29/357,328**

(22) Filed: **Mar. 10, 2010**

(51) **LOC (9) Cl.** **03-01**

(52) **U.S. Cl.** **D9/318; D9/425; D9/434; D32/53**

(57) **CLAIM**

The ornamental design for a container, as shown and described.

DESCRIPTION

FIG. 1 is a perspective view of a container showing our design;

FIG. 2 is a front view, the rear view being a mirror image thereof;

FIG. 3 is a left side view, the right side being a mirror image thereof;

FIG. 4 is a top view thereof; and,

FIG. 5 is a bottom view thereof.

The broken lines are included for the purpose of illustrating portions of the container that form no part of the claimed design.
